CLAIM

The ornamental design for a “hanging accessory bag with pocket arrangement,” as shown and described.

DESCRIPTION

FIG. 1 is a perspective view of a hanging accessory bag with pocket arrangement showing the appearance of our new design when closed;

FIG. 2 is a similar perspective view thereof showing the appearance of the design when opened;

FIG. 3 is a sectional perspective view thereof taken along line 3—3 in FIG. 2, showing the appearance of an interior of a front panel thereof, with open pockets revealing the design features thereof;

FIG. 4 is a rear elevational view thereof;

FIG. 5 is a front elevational view thereof;

FIG. 6 is a right side elevational view, the left side elevational view being a mirror image thereof;

FIG. 7 is a top plan view thereof; and,

FIG. 8 is a bottom plan view thereof.
